[57] CLAIM

The ornamental design for a pair of chair arms, as shown and described.

DESCRIPTION

FIG. 1 is a prospective view from the front and to one side of the arms of a chair. The chair is shown in dotted outline and does not form part of the design;

FIG. 2 is a front elevational view of the arms of FIG. 1;

FIG. 3 is a side elevational view of an arm of FIG. 1, the opposite arm being a mirror image thereof;

FIG. 4 is a rear elevational view of the arms of FIG 1; and,

FIG. 5 is a top plan view of the arms of FIG. 1.
